UNITED STATES PATENT OFFICE.

JOSEPH LINDBURG, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed May 23, 1925. Serial No. 32,288.

This invention relates to stencil-attachments for front-strike typewriting machines in which a stencil-card is line-spaced by raising the card in flat condition step by step. 5 A machine of this type is disclosed in patent to Elliott, 1,378,771, dated May 17, 1921.

Said type of machine is provided with a rock-frame mounted at the rear, and the card is clamped to the forward end of the frame. 10 A line-space mechanism raises the frame.

One of the features of this invention relates to means for preventing accidental displacement of the rock-frame, as when the machine is tipped back for any reason. In drop desks, 15 the machine is secured to the desk-top and is lowered into an opening of the desk in an inclined position, and the machine may be jerked, throwing the stencil-frame against the walls of the desk and damaging both the 20 stencil-device and the machine. By this invention locking means are provided to prevent the displacement of the stencil-frame relative to the carriage of the machine upon which the stencil-device is mounted.

25 Means are also provided to facilitate the attaching to and detaching from an Underwood standard typewriter a stencil-device of the Elliott type. Novel locking means comprise slotted studs fast to the carriage, the 30 slots of which receive flat locking pieces mounted on the stencil-device.

In some cases it is desirable to use a continuous strip of celluloid around the platen, the strip being held thereon by means of the 35 usual feed-rolls.

One of the features of the invention relates to means, including a plate, for controlling the rotation of the platen when the stencil-device is attached to the machine, in order 40 to protect the type from striking a clip which normally supports the celluloid strip around the platen. The plate is swingable out of engagement with the platen to permit the continued feeding of the celluloid strip.

45 Other features and advantages will herein-after appear.

In the accompanying drawing,

Figure 1 is a plan view of the stencil-device as applied to an Underwood standard type- 50 writing machine.

Figure 2 is a side view, in elevation, showing the device off the machine.

Figure 3 is a perspective view of the lock

and the means for preventing the full rotation of the platen. 55

Figure 4 is a side view, in elevation, of the stencil-device applied to an Underwood standard typewriting machine.

Figure 5 is a modification of the backing shown in Figure 4, and shows an endless celluloid strip around the platen. 60

A stencil-card, not shown, is placed in a recess at the free end of a rockably-mounted frame 10 and is held therein by means of jaws 11, operable by a finger-piece 12, which is 65 pressed against a second finger-piece 13 fast to the frame. Then the card is lowered to the printing position and is cut by the successive striking of the types 14 against a platen 15, in a manner shown in said patent to Elliott. The frame 10 comprises side arms 16 70 connected by a reinforcing bar 17 and is fulcrumed upon a cross-bar of a base-frame 18 having end-members 19 designed to fit over the cover-plates 20 on the ends of the platen-frame of the machine. 75

The stencil-device is herein illustrated in the form of an attachment to the platen-frame of an Underwood standard typewriting machine, and it is one of the features 80 thereof that the same may be quickly attached to and removed from the machine to thus permit the use of the machine either as a stencil-cutter or as an ordinary typewriter.

To this end, some changes are made to the 85 machine itself previous to receiving the stencil-device thereon. However, the changes made on the machine are such that will not interfere with the regular operation of the machine as a typewriter. One of the changes 90

relates to the addition of studs 21 to the end cover-plates 20 of the platen-frame. Said studs are provided with slots 22 for receiving pieces 23 to lock the stencil-device to the cover-plate. The pieces 23 are pivotally 95 mounted at 24, and are held on the end members 19 by means of a headed stud 25 engaging with an arcuate slot 26. In order to facilitate the operation of the pieces 23, they are provided with bent tabs 27 which are 100 actuated by means of the fingers against the tension of springs 28 which hold the pieces in engagement with the slots 22 of the studs 21. The members 19 are provided with elongated slots 29 to clear screws 30 on the platen-frame in any forward or rearward-adjusted

position of the end plates 20; it will be noted that these plates are provided with smaller slots through which screws 30 pass, which slots are provided so that the stencil-device 5 can be adjusted forwardly and rearwardly by moving the cover-plates in either direction. This provides means whereby the stencil-card may be adjusted to proper position against the platen of the typewriting 10 machine.

In this invention, there is provided a celluloid strip 46, the same as shown in the application of Alfred G. F. Kurowski, Serial No. 708,332, filed April 23, 1924 (now Patent 15 No. 1,608,219, dated November 23, 1926), which serves as a backing for the platen to facilitate the cutting of the stencil. The strip is held on the platen by means of a metal clip, and, in order to prevent the clip 20 from being positioned in the striking field of the types, there is also provided a stop-device 31 as an abutment for a projecting pin on the end of the platen. Stop-device 31 has sufficient length so that the pin on the platen 25 will engage either end of it before the metal clip gets to the striking field of the types. The stop-device is pivotally mounted upon a shaft 32 and secured thereto by means of a set screw 33 that it may be swung out of the 30 way, as shown in Figure 5, in case it is desired to use a continuous strip of celluloid 34, such as disclosed in the application of Jesse A. B. Smith, Serial No. 11,952, filed February 27, 1925 (now Patent No. 1,623,455, 35 dated April 5, 1927).

In order that the rockably-mounted frame of the stencil-device may be locked against displacement relative to the carriage, there is provided a locking device 35, which is pivotally mounted upon the shaft 32 on the fixed 40 frame and engages the shaft 36, rotatably mounted on the rocking frame. The locking device 35 is made of a rectangular sheet-metal strip wound around the shaft 32 at 37, 45 forming an eye and extending upwardly, forming a resilient hook 38 for embracing the hub 39 of a finger-wheel 40. The locking device is made slightly shorter than the distance between the centers, so that the hook 50 will slightly spring for resiliently holding the locking device in engagement. When it is desired to operate the machine, the locking device is thrown rearwardly to a position shown in dot-and-dash lines in Figure 4, so as 55 to permit the raising of the free end of the frame by the action of the finger-wheel 40 actuating a cam 41 which is backed by a roller 42 borne by the shaft 36. As the cam 30 is rotated, a spring, not shown, is wound around the shaft and the cam is held in place by a pawl 43 engaging with a ratchet 44, the pawl being released at the same time the jaws are opened by a link 45 operatively connecting the two members.

Variations may be resorted to within the

scope of the invention, and portions of the improvements may be used without others.

Having thus described my invention, I claim:

1. The combination with a typewriting machine having a revoluble platen, a carriage, and typing instrumentalities, of a stencil device borne by said carriage and effective to present a stencil-card to the printing field in front of the platen, said stencil device comprising a fixed frame, a shaft on the fixed frame for supporting a rockable frame thereon and means for raising the free end of the rockable frame to line-space the card, and means for locking said rockable frame against displacement relatively to the carriage. 70

2. The combination with a typewriting machine having a revoluble platen, a carriage, and typing instrumentalities, of a stencil device borne by said carriage and effective to present a stencil-card to the printing field in front of the platen, said stencil device comprising a fixed frame, a shaft on the fixed frame for supporting a rockable frame thereon and means for raising the free end of the rockable frame to line-space the card, and means for locking said rockable frame against displacement relatively to the carriage, said last-mentioned means comprising a latch pivotally mounted on the fixed frame of the stencil device and engaging with the shaft on the rockably mounted frame. 80

3. A stencil-card-holding unit for typewriting machines, including a base-frame having members shaped to engage the ends of the platen-frame of the machine and detachably support said unit in superimposed relation with the platen-frame, and a swingable stencil-card holding and feeding mechanism mounted upon said base-frame, said base-frame and mechanism having co-operating parts operable to detachably lock said mechanism against swinging movement on the base-frame, one of said parts having a resiliently hook-shaped portion to engage and bind upon the other part. 100

4. A stencil-card-holding unit for typewriting machines, including a base-frame having members shaped to engage the ends of the platen-frame of the machine to detachably support said unit in superimposed relation with the platen-frame, and a swingable stencil-card holding and feeding mechanism mounted upon said base-frame, said base-frame and mechanism having co-operating parts operable to detachably lock said mechanism against swinging movement on the base-frame, said parts including a rigid member and a pivotally-mounted resilient member shaped to detachably engage the rigid member and effective to frictionally bind upon the latter by virtue of its own resiliency. 115

5. A stencil-card-holding unit for typewriting machines, including a base-frame 120

having members shaped to engage the ends of the platen-frame of the machine to detachably support said unit in superimposed relation with the platen-frame, and a swingable 5 stencil-card holding and feeding mechanism mounted upon said base-frame, said base-frame, and mechanism having co-operating parts operable to detachably lock said mechanism against swinging movement on the base- 10 frame, said parts including a rigid member and a pivotally-mounted resilient member shaped to detachably engage the rigid member and effective to frictionally bind upon the latter by virtue of its own resiliency, said re- 15 silent member also having a finger-piece to aid in engaging and disengaging the member.

6. The combination with a typewriting machine having a revoluble platen and a carriage therefor, of a stencil device having 20 means for temporarily attaching the same to the carriage, said stencil device comprising a rockably mounted frame and means for rais- 25 ing the free end of the frame to line-space a stencil-card supported by its uppermost edge upon the free end of said frame, and means for locking said rockable frame against dis- placement relatively to the carriage.

7. The combination with a typewriting machine having a revoluble platen and a car- 30 rriage therefor, of a stencil device having means for temporarily attaching the same to the carriage, said stencil device comprising a rockably mounted frame and means for

raising the free end of the frame to line- 35 space a stencil-card supported by its upper- most edge upon the free end of said frame, and means for locking said rockable frame against displacement relatively to the car- riage, said last-mentioned means including a hook mounted on a fixed shaft of the stencil 40 device and co-operating with a shaft mounted on the rockable frame, said hook being positioned on the shaft by means of two set collars.

8. The combination with a typewriting machine having a platen, a carriage, and typ- 45 ing instrumentalities, of a detachable frame borne by the carriage, a displaceable frame carried by said detachable frame above the platen, means for elevating the displaceable frame above the platen step by step to line- 50 space a card, and a releasable latch-piece car- ried by the detachable frame and engageable with the displaceable frame to releasably se- 55 cure the latter against accidental displace- ment when not in use.

9. The combination with a typewriting machine having a revoluble platen and a traveling carriage therefor, of a stop as- 60 sociated with the platen, said stop being positionable to intercept a pin carried by the platen, whereby to limit the rotation thereof, said stop being also swingable away from the platen to a position out of the path of said pin, to permit free rotation of said platen.

JOSEPH LINDBURG.
